CLAIM

The ornamental design for a frozen confection mold, as shown and described.

DESCRIPTION

FIG. 1 is a rear elevational view of a frozen confection mold showing my new design;

FIG. 2 is a left side elevational view thereof, the opposite side being substantially similar except for the omission of the connecting strap;

FIG. 3 is a front elevational view thereof;

FIG. 4 is a top plan view thereof; and

FIG. 5 is a bottom plan view thereof.

FIG. 1
